UNITED STATES PATENT OFFICE.

JOSEPH W. V. RAWLINS, OF HOUGHTON, MICHIGAN.

STEAM ROCK-DRILL.

SPECIFICATION forming part of Letters Patent No. 280,668, dated July 3, 1883.

Application filed March 12, 1883. (No model.)

To all whom it may concern:

Be it known that I, JOSEPH W. V. RAWLINS, a citizen of the United States, residing at Houghton, in the county of Houghton and State of Michigan, have invented certain new and useful Improvements in Rock-Drills, of which the following is a specification.

My present invention has relation to the improvement of rock-drilling machines, and in particular does it relate to the means whereby the rotation of the drill is effected in order that its cutting-points may be presented in different positions at each succeeding stroke.

In the operation of drilling it frequently happens that the drill-points strike an oblique blow, which tends with such force to turn the drill that in machines as at present constructed there is constant danger of breaking the mechanism by which the drill is rotated.

The object of this invention is to provide improved means for effectually rotating the drill, and by which the danger of breakage incident to striking an oblique blow will be entirely avoided. This object I have accomplished by the mechanism hereinafter described, illustrated in the accompanying drawings, and particularly defined in the claims at the end of the specification.

Figure 1 is a view in vertical section of a portion of a rock-drilling machine embodying my invention. Fig. 2 is a view in transverse section on line $x-x$ of Fig. 1. Fig. 3 is a view in transverse section on line $x'-x'$, (parts being left in elevation,) showing the position of the ratchet and connected mechanism when operating the ratchet-wheel for rotating the drill. Fig. 4 is a detail top view of the main piston with the bushing to receive the turning-bar.

A designates the main cylinder of the drilling-machine, which is provided with the usual induction and exduction pipes for steam or compressed air, and has its lower end closed by a cap, A', through which passes the drill-stock B, keyed to the main piston C. This main piston is bored out centrally, as shown at c, to permit its free movement upon a square turning-bar, D, which fits within the bushing e of the piston. The upper portion of this turning-bar is rounded and furnished with flange d, which rests within a seat in the bottom e of what I designate the "ratchet-casing" E, which is bolted by lugs e' to suitable lugs

(not shown) upon the sides of the main cylinder. In the top e' of the casing E is journaled the end of the turning bar, and within this casing, and firmly keyed to the turning bar, is held the ratchet-wheel F, which, when moved, serves to impart rotation to the turning bar, and consequently to the main piston, the drill-stock, and the drill. The movement of this ratchet-wheel is effected by means of the ratchet G, journaled to the hinge-piece G', carried by the ratchet-piston H, moving within the supplemental cylinder H', which is preferably formed integral with the casing E, and the ends of which are closed by the threaded caps h h'. The piston H is formed, as shown, with the bore h', in which fits the rod I, which is held by the cap h, and carries the spiral spring K, the ends of which rest within sockets in said cap and piston.

In the bottom of the ratchet-casing, as shown in dotted lines, Figs. 1, 2, and 3, is formed the steam-passage L, which, by the ports l and l', connects the front end of the supplemental cylinder H' with the top of the main cylinder A. Upon the inside of the ratchet-casing is formed the stud M, which serves to retain the ratchet out of gear with its wheel when the ratchet-piston is in the forward part of the cylinder, as shown in Fig. 2 of the drawings. A spring, m, attached to the side of the casing, forces the ratchet into gear when released from the stud.

From the construction of parts as thus defined the operation will be seen to be as follows: As the main piston approaches the end of its back stroke, it is met by the steam issuing through the upper induction-port, and is forced forward again. At the same moment steam issues from the main cylinder through the passage L into the supplemental cylinder, and in so doing forces back the supplemental piston, thus compressing the spiral spring K and causing the ratchet to impart to its ratchet-wheel a partial revolution, which is communicated to the turning bar, the main piston, and the drill. When the steam is exhausted from the main cylinder, it is also exhausted from the supplemental cylinder, and by the connection shown of the pawl to the supplemental piston no steam is allowed to pass into the ratchet-wheel chamber. The spiral spring now at once forces the ratchet-piston forward, and the end of the ratchet strikes and passes beneath

the stud M, and is thus thrown out of gear with the ratchet-wheel, and so remains until the succeeding stroke. It will thus be seen that the main piston is free to revolve in case of striking an oblique blow at any time, thereby avoiding all danger of breaking the mechanism whereby the rotation of the drill is effected.

Although I have stated in the foregoing description what I regard as the best embodiment of my invention, it will be readily understood by those skilled in the art that it may be modified without departing from the spirit of the invention, and I do not wish to be understood therefore as restricting myself to the precise details set out.

Having thus described my invention, what I claim as new, and desire to secure by Letters Patent, is—

20 1. In rock-drills, the combination, with the main cylinder and piston, of a turning bar, a ratchet-wheel keyed to said bar, a supplemental cylinder and piston, and a ratchet for turning the ratchet-wheel connected to the side of the supplemental piston, substantially as described.

25 2. In a rock-drill, the combination, with the main and supplemental pistons and the turning bar, of mechanism for revolving said turning bar and means for automatically discon-

nnecting said revolving mechanism from the turning bar, substantially as described.

3. In rock-drills, the combination, with the main cylinder and piston and the turning bar, of a ratchet-wheel connected to said turning bar, a ratchet for operating said wheel, and means for throwing said ratchet out of gear, substantially as described. 35

4. The combination, with the main cylinder and piston, of a turning bar, a ratchet-wheel, 40 a ratchet, and a spring-seated supplemental piston for actuating said ratchet, substantially as described.

5. The combination, with the main cylinder and piston, of the turning bar, the ratchet-wheel, the ratchet, the supplemental cylinder and spring-seated ratchet-piston, and a passage or channel connecting said main and supplemental cylinders, substantially as described. 45

6. The combination, with the main cylinder and piston, of the turning bar, the ratchet-wheel, the ratchet and mechanism for operating the same, and the ratchet-casing provided with a stud for holding the ratchet out of action, substantially as described. 50
